UNITED STATES PATENT OFFICE.

EDMUND GURNEY, OF PORTLAND, OREGON, ASSIGNOR TO P. J. BURNS, OF PORTLAND, OREGON.

BRICKMAKING-MACHINE.

1,131,627.

Specification of Letters Patent.

Patented Mar. 9, 1915.

Application filed February 8, 1912. Serial No. 676,391.

To all whom it may concern:

Be it known that I, EDMUND GURNEY, a citizen of the United States, residing at Portland, in the county of Multnomah and State of Oregon, have invented certain new and useful Improvements in Brickmaking-Machines, of which the following is a specification.

My previous application for patent filed 10 January 16, 1912, Serial Number 671,439, discloses certain improvements in clay working machinery, embodying particularly a special construction of brick cutting table or machine having automatically operable 15 means associated therewith for supporting brick after they have been cut and for transferring the spread brick to a conveyer.

The present invention appertains to the means above referred to and includes primarily 20 differently operating means for effecting the transfer of the cut spread brick from the cutting table to the conveyer, which last mentioned means is especially adapted for use in connection with certain 25 types of cutting machines or tables, and may be advantageously used in substitution for the equivalent mechanism set forth in my previous application. In my previous application, I also describe the use of a stop which 30 is automatically actuated in the movement of the carriage on the cutting table, whereby to engage with the cut brick at a predetermined time to shift said brick from a spreading pallet to a portable pallet or to a 35 conveyer.

The present invention embodies certain operating means for said stop to restore the same to its normal position out of the path of movement of the brick at a predetermined time in the operation of the machine.

For a full understanding of the present invention, reference is to be had to the following description and to the accompanying drawings, in which—

Figure 1 is a side elevation of a brick cutting machine or table, showing the invention applied thereto. Fig. 2 is a view showing more clearly the conveyer as arranged in relation to the portable pallet and the

bracket means for supporting the depressible delivery arms of the carriage. Fig. 3 is a side view of the parts shown in Fig. 2 and other adjacent parts, the carriage being broken away. Fig. 4 is a detail front elevation bringing out more clearly the standard 55 supporting the bell crank lever which is operable by the main lever and connected for actuation of the stop.

Throughout the following detail description and on the several figures of the drawings, similar parts are referred to by like reference characters.

As shown most clearly in the drawings, the cutting table or machine in connection with which the present improvements are 65 used is of a conventional type, embodying the frame 1, the main operating lever 2, the carriage 3 and the stop plate 4. The operating lever 2 is mounted upon a shaft 5 in the customary manner, arms of said shaft being 70 connected by links 6 with the carriage 3 so that the carriage may be reciprocated upon the frame 1 by means of the back and forth movement of the lever 2. The cutting wires 7 are carried back and forth in the cutting 75 operation by the carriage 3, being attached to the carriage in the customary manner.

As in my application previously referred to, I mount upon the carriage 3 a spreader pallet 8 composed of a plurality of units 80 adapted to be spread automatically as the carriage 3 is moved to the right in Fig. 1 and to be closed together as the carriage is moved to the left, referring to the same figure of the drawings. At one side of the pallet 8 are mounted a plurality of transfer rolls 9, said rolls extending transversely of the frame of the table, parallel with the pallet 8 and between said pallet and delivery arms 10 which are carried by the extreme ends of the sides of the carriage opposite the end of the machine at which the cutting mechanism is located.

The delivery arms 10 aforesaid are hingedly or pivotally connected with the carriage at 11 and springs 12 connect adjacent end portions of the carriage and said arms for a purpose to be hereinafter described.

Brackets 13 secured to the adjacent end of the frame 1 of the machine are formed with laterally projecting supporting arms 14 having rollers 15 journaled at their outer extremities, said brackets being also formed with the vertical arms 16 having the anti-friction rollers 17 at their upper ends. At the outer ends of the delivery arms 10, each arm has a combined stop and anti-friction roller 18 mounted thereon and projecting slightly above the surface of the arm. A portable pallet 19 is shown in position on the delivery arms 10, in Fig. 3 of the drawings, and bricks 20 are illustrated as carried on the pallet.

Standards 21 are detachably mounted on the frame 1 near the delivery end of the frame and these standards carry the stop 22 which is vertically movable in guide slots 23 on the standards. Projections 24 at the ends of the stop 22 are engageable by catches 25 pivoted to the standards 21 and the catches 25 have arms which are in the path of movement of the horizontal arms 26 of the carriage 3, said arms 26 having the upper ends of the cutting wires attached thereto. Connected with the stop 22, preferably at its middle portion, is a wire, rope, or other flexible connection 27 passing over a pulley 28 above the machine and extending to the long arm of the crank lever 29. The lever 29 is pivoted to the upper end of a standard 30 detachably secured to the floor or base upon which the machine is arranged and located at one side of the lever 2 so that, in the movement of the lever 2, a lug 31 of a detachable collar 32 on the lever will be adapted to strike the short vertical arm of the lever 29 and tilt the latter in the operation of the machine.

The operation of the machine in detail will now be described: The bar or stick of clay which is to be cut up to form the bricks is fed upon the cutting table or machine in the customary way until it strikes the stopping plate 4. The operator of the machine then swings the lever 2 to the left, as shown in Fig. 1, thereby moving the carriage 3 until the stick or bar of clay is cut into separate bricks by means of the cutting wires 7. During the cutting operation, the movement of the carriage 3 slides the pallet 8 under the bricks and the operator will then move the lever 2 to the right into the dotted line position in Fig. 1, thereby carrying the bricks bodily on the pallet toward the delivery end of the machine. The bricks in the above operation are spread by means of coöoperating with the various units of the pallet 8 and fully set forth in my previous application for patent. When the carriage 3 reaches the limit of its delivery movement, as shown in dotted lines in Fig. 1, the bricks will be supported by the pal-

let 8 and the stop 22 will have been released from the catches 25 and will drop in rear of the bricks on the side toward the cutting mechanism so that when the operator again moves the lever 2 to the left, the stop 22 will sweep the bricks in spread condition, from the pallet 8 over the rolls 9 onto the portable pallet 19, shown in Fig. 3. At this stage of the operation, the parts appear as in full lines in Fig. 3 and the next right hand movement of the lever 2 initially causes the lug 31 thereon to strike the vertical arm of the lever 29, thereby exerting a pull upon the connection 27, raising the stop 22 until the latter is supported again by the catches 25. Subsequent movement of the lever 2 and carriage 3 in the right hand direction will move the delivery arms 10 into the dotted line position shown in Fig. 3, said arms 10 sliding over the rollers 17 and 15. By reason of the weight of the bricks on the pallet 19, the arms 10 will be depressed into inclined positions and the lowering movement of the arms permits the pallet now supported thereby to be engaged by the conveyer 33 and carried off to the drying means. Just as soon as the pallet 19 has been engaged and removed from the arms 10, by the conveyer 33, the springs 12 act to lift the arms 10 so that a fresh empty pallet 19 may be placed on the arms and not engaged by the conveyer even though the lever 2 is at its right hand limit of movement. In other words, the weight of the fresh pallet 19 alone would not be sufficient to depress the arms 10. The rollers 18 on the delivery arms 10 perform a peculiar function in that as the bricks 20 are shifted from the pallet 8 over the rolls 9 to the pallet 19, there is a tendency for the pallet 19 to be shoved off of the supporting arms 10. The outer edge of the pallet 19, however, rests against the rollers 18, and the latter constitute stops preventing the movement referred to. However, in the delivery of the pallet 19 and bricks 20 to the conveyer 33, it will be apparent that the depression of the arms 10 permits engagement of the conveyer with the pallet 19 in such a way that the latter is the more readily carried from the arms 10 because in this movement the rollers 18 act as anti-friction means between the under side of the pallet and the arms.

I contemplate to employ any automatically operating means in lieu of the parts 27, 29 and 31 for accomplishing the raising of the stop 22 at the proper time in the operation of the machine. It is contemplated furthermore to make further modifications in the details of construction as hereinbefore presented and consistent with the broader spirit of the invention and scope of the claims hereto appended.

Having thus described the invention, what is claimed as new is:

1. In brick making machinery, the combination of a conveyer, means for delivering brick to said conveyer comprising a carriage, delivery arms on said carriage, means for delivering brick to said delivery arms, means for moving the carriage bodily toward and from the conveyer, and means 10 connecting the arms and the carriage for relative movement of the arms and conveyer to deliver the bricks to the conveyer.

2. In a machine of the class described, the combination of a conveyer, a carriage, delivery arms movably mounted on the carriage, means for supporting said delivery arms to normally prevent delivery movement of the same with respect to the conveyer, means for moving the delivery arms 15 to a delivery position in respect to the conveyer, and means whereby the delivery arms may be depressed by weight thereon when said arms are moved to a predetermined point in respect to the supporting means 20 aforesaid, and pallet engaging stop means on the said arms.

3. In a machine of the class described, the combination of a conveyer, a carriage, delivery arms movably mounted on the carriage, means for supporting said delivery arms to normally prevent delivery movement of the same with respect to the conveyer, means for moving the delivery arms to a delivery position in respect to the conveyer, means whereby the delivery arms by weight thereon when said arms may be depressed are moved to a predetermined point in respect to the supporting means aforesaid, and combined stop and anti-friction 35 rollers carried by the delivery arms.

4. In a machine of the class described, the combination of a carriage, delivery arms at one end of the carriage, means including an operating lever for moving the carriage 45 back and forth to transfer the bricks from one point on the carriage to said delivery arms, and means normally supporting the delivery arms in an elevated position, and connections between said arms and the carriage adapted to allow a downward depositing movement of the arms when the same are projected from their supporting means 50 at a predetermined point in the movement of the carriage.

5. In a machine of the class described, the combination of a back and forth movable brick delivery carriage, delivery arms at one end of the carriage and adapted to support a pallet, anti-friction means normally 55 supporting the delivery arms in a position to receive bricks thereon, means for moving the carriage and arms so as to project from said supporting means, a conveyer, and pivotal connections intermediate said arms and

carriage whereby a delivery movement of 60 the delivery arms to a plane below that of the conveyer may take place when the delivery arms are projected from the supporting means above mentioned.

6. In a machine of the class described, the combination of a reciprocatory brick delivery carriage, yieldable delivery arms connected with the carriage at one end of the latter, means for delivering bricks to said arms, means for effecting delivery movement 75 of the carriage with the arms, supporting means for the arms whereby the latter may yield at a predetermined point in their movement, and a conveyer arranged to engage the bricks on the supporting arms 80 when the latter yield and project below the conveyer.

7. In a machine of the class described, the combination of a brick delivery carriage, yieldable delivery arms mounted thereon, 85 means for delivering bricks to said arms, means for effecting delivery movement of the carriage with the arms, anti-friction means engaging the delivery arms and permitting yielding of the latter at a predetermined point in their delivery movement, a conveyer arranged to engage the bricks on the supporting arms when the latter yield 90 in their delivery movement, and resilient connections between the delivery arms and the carriage.

8. In a machine of the class described, the combination of a brick delivering carriage, a receiving pallet thereon, delivery arms, a portable pallet on said delivery arms, means 100 for transferring the brick from the receiving pallet to the portable pallet, a conveyer, and stop means on the delivery arms for preventing shifting of the portable pallet on to the conveyer as the bricks are transferred thereto.

9. In a machine of the class described, the combination of a brick delivering carriage, a receiving pallet thereon, delivery arms, a portable pallet on said delivery arms, means 110 for transferring the brick from the receiving pallet to the portable pallet, rollers carried by the delivery arms and constituting stops for preventing unauthorized shifting of the portable pallet as bricks are delivered thereto, and conveyer means for removing the portable pallet from the delivery arms, said rollers constituting anti-friction bearings for the portable pallet during the operation of the last mentioned means.

10. In brick making machinery, the combination with a portable pallet, of instrumentalities transferring bricks to said pallet, a conveyer, and means coacting with the pallet whereby automatic engagement of 125 said pallet with the conveyer may be effected and the former carried off to a suitable point of deposit.

11. In brick making machinery, the combination of a carriage, a support mounted thereon, a portable pallet supported by the carriage, a conveyer arranged to carry off the portable pallet, means for shifting the bricks from the support to the portable pallet, and means coöperating with the pallet whereby relative movement of the pallet and conveyer may be effected other than the

travel of the latter to engage said parts for 10 the purpose described.

In testimony whereof I affix my signature in presence of two witnesses.

EDMUND GURNEY.
